CLAIM

The ornamental design for an eyeshadow, lipstick and powder compact with applicators, as shown and described.

DESCRIPTION

FIG. 1 is a front elevational view of an eyeshadow, lipstick and powder compact with its lid open top, showing my design;

FIG. 2 is a rear elevational view of the eyeshadow, lipstick and powder compact of the present invention with its lid open;

FIG. 3 is a left side elevational view of the eyeshadow, lipstick and powder compact of the present invention with its lid open;

FIG. 4 is a right side elevational view of the eyeshadow, lipstick and powder compact of the present invention with its lid open;

FIG. 5 is a top plan view of the eyeshadow, lipstick and powder compact with its lid open and illustrating three compartments for respectively containing eyeshadow, lipstick and facial powder as well as a pair of applicator comprising a first applicator with a handle and brush and a second applicator with a handle having a brush at one end of the handle and a flexible pad at the other end; and, FIG. 6 is a bottom plan view of the eyeshadow, lipstick and powder compact with its lid open.
